DESIGN FOR A DRESS

Concetta Jaccarino, Brooklyn, N. Y.

Application December 26, 1941, Serial No. 104,847

Term of patent 3½ years

To all whom it may concern:

Be it known that I Concetta Jaccarino, a citizen of the United States, residing in Brooklyn, New York city, in the county of Kings and State of New York, have invented a new, original, and ornamental Design for a Dress, of which the following is a specification, reference being had to the accompanying drawing, forming part hereof.

I claim:

The ornamental design for a dress, substantially as shown.

CONCETTA JACCARINO.
